BUFFING WHEEL

George R. Churchill, Cohasset, Mass.

Application August 9, 1950, Serial No. 178,490

2 Claims. (Cl. 51—193)

1

This invention relates to a buffing wheel.

In general, the invention is an improvement upon the buffing wheel forming the subject matter of my United States Patent No. 2,146,284 and has for an object to provide a novel and improved buffing wheel of the type illustrated in said patent which may be economically manufactured and which may be used with advantage in performing buffing operations for which such prior buffing wheels are unsuited.

Another object of the invention is to provide a novel and improved buffing wheel of the type specified having duplex buffing sections and which is further characterized by structure presenting a buffing surface of substantially uniform density, increased flexibility, and a greater capacity for retaining a buffing compound than prior buffing wheels of which I am aware.

With these general objects in view, and such others as may hereinafter appear, the invention consists in the buffing wheel hereinafter described and particularly defined in the claims at the end of this specification.

In the drawings illustrating the preferred embodiment of the invention, Fig. 1 is a front elevation of the present buffing wheel; Fig. 2 is a side view of the same; Fig. 3 is a cross-sectional view taken on the line 3—3 of Fig. 1; Fig. 4 is a cross-sectional view, similar to Fig. 3 and illustrating a modified form of the present buffing wheel; Figs. 5 to 8 are diagrammatic views illustrating the steps preferably followed in folding one form of a buffing element employed in producing the present buffing wheel; Figs. 9, 10, and 11 are diagrammatic views illustrating the steps preferably followed in folding a modified form of buffing element employed in producing the present buffing wheel; and Fig. 12 is a cross-sectional view taken on the line 12—12 of Fig. 4, and illustrating the modified form of buffing element shown in Fig. 11.

In general, the present invention contemplates a cloth buffing wheel section adapted to be mounted side by side with other sections and clamped together on a rotary arbor to form a buffing wheel unit of the desired width. The commercial individual buffing wheel sections illustrated in my patent above referred to comprised a ring of connected and radially extended buffing elements wherein each element was formed by folding a relatively wide sheet of cloth to form a relatively flat buffing element of substantial width and then stitching the multiple layers of folded cloth longitudinally of the elements. Such elements were then connected to

form a ring wherein the flat or narrow edges of the elements were disposed in substantial alignment at right angles to the axis of the arbor whereby to produce a relatively stiff, narrow, and extremely durable buffing section particularly adapted for use in buffing relatively hard materials.

In accordance with the present invention, a buffing wheel section is provided having a relatively wider and more flexible working face adapted for universal use to effect an efficient buffing operation upon a wide variety of work. The buffing wheel section herein illustrated comprises one or more rings of radially extended buffing elements, the present buffing section being preferably illustrated in duplex form, and in which each buffing element is made up of a relatively short length of cloth folded to produce a multiple-ply element which is itself folded longitudinally so that it has wings extending circumferentially in the same direction from the fold and is thus substantially V-shaped in cross section. In practice, adjacent connected elements are relatively closely spaced and arranged in nesting relation with the points of the V aligned vertically at right angles to the axis of the ring so that when assembled in ring form, the free ends of the V-shaped multiple elements spread out laterally to present a relatively wide buffing face of substantially uniform density and moderate flexibility. The plurality of folds in the free ends of the relatively closely spaced and multiple-ply V-shaped elements in nested relation also presents, in appearance, a honeycomb structure that provides a maximum number of pockets in which the buffing compound may be retained. When made in duplex form, the nested V-shaped elements of adjacent rings are preferably arranged in opposite directions so that a duplex section may be placed on an arbor to rotate in either direction.

In a modified form of the invention, the buffing elements may be folded so that the free ends of the buffing elements present a substantially N-shape in cross section, adjacent relatively closely spaced N-shaped elements in a buffing ring being also arranged in nested relation to provide a relatively wide and resilient buffing surface and having pockets for the buffing compound formed in both directions by the reversely folded portions of the N.

In each embodiment of the invention the points or folds of the V or N-shaped elements are arranged in vertical nested alignment about the

2

periphery of the ring forming folds or pleats having legs or wings adapted to spread apart laterally when engaged by the work to be buffed, thereby covering a greater area of the work with maximum uniformity and without effecting streaking of the work.

Referring now to the drawings, 10 represents a duplex buffering wheel section embodying the present invention, each duplex section comprising two rings 12 of connected and radially extended cloth buffering elements indicated at 14. In practice, the buffering elements 14 may be held together adjacent one end thereof by wires 16 woven around the individual buffering elements to form a chain of connected elements, the requisite length of such a chain of connected buffering elements being formed into a circular shape and joined at its ends to form a closed ring 12. In the illustrated embodiment of the invention, two of such rings may be secured to a central supporting disk 18 to form a buffering section, the rings being preferably separated slightly by an annular spacing member indicated at 20.

In general, in one embodiment of the invention, as illustrated in Fig. 3, the rings 12 may be mounted on and secured to one side of the supporting disk 18, or as illustrated in Fig. 4, in another embodiment of the invention the supporting disk 18 may be disposed intermediate of the two rings with a ring secured to each side of the disk.

As illustrated in Figs. 5 to 8, one form of buffering element 14 preferably employed in producing the present buffering section may be formed by first folding an extended length of cloth 22 twice upon itself to form a four-ply strip 24, as shown in Figs. 5 and 6, and then folding the longitudinal or marginal edges 26, 28 of the four-ply strip inwardly in overlapping relation, each edge being folded inwardly about one-third of the width of the four-ply strip, with one wing portion reversely folded inwardly on itself, as indicated in Figs. 7 and 8, thus forming a twelve-ply strip. The reversely folded wing, of course, contains more plies than the other wing which is more flexible. A plurality of such strips or buffering elements 14 are then connected together adjacent one end thereof by the weaving wires 16, leaving the opposite ends and unconfined portions of the elements free to assume a substantially V-shape, as shown in Fig. 8, one leg of the V having eight plies comprising the folded portions 24, 26, and the other leg having four plies comprising the folded portion 28, two of which plies comprise the exposed marginal edges 34 of the length of cloth 22.

Another form of buffering element 140 which may be employed in producing the present buffering section, and in which the marginal edges of the cloth strip are concealed, is illustrated in Fig. 11, which may be formed by folding opposed edges of a length of cloth 36 inwardly to meet at a point 38 offset to one side of a medial line of the two-ply strip thus formed, as shown in Fig. 9, and then folding the two-ply strip along the offset line 38 confining the marginal edges 39 and forming a four-ply strip 40 having a two-ply extended portion 42, as shown in Fig. 10. The strip thus formed is then folded into a substantially N shape, the two-ply extended portion 42 being folded upwardly and over the adjacent edge of the four-ply portion 40, and the four-ply portion being folded downwardly and upon itself to form a ten-ply strip or buffering element 140, as shown in Fig. 11. The ten-ply strip is like-

wise confined at one end by the weaving wires, as described, leaving the opposite ends and unconfined portions of the buffering element free to spread open and assume a substantially N shape, one leg 44 of the N having four plies including the concealed edges 39 of the strip, the intermediate portion 46 of the N also having four plies, and the other leg of the N comprising the extended portion 42 having two plies.

From the description thus far, it will be observed that the unconfined and substantially V-shaped and/or N-shaped cross-section buffering elements thus formed provide a relatively wide buffering or working face having substantial resiliency and flexibility. In practice, the V and/or N-shaped buffering elements are preferably connected together at one end by the weaving wires in relatively closely spaced relation and in a manner such that the outer or unconfined portions of the elements are arranged in nested relation, as illustrated in Figs. 2 and 12, thus providing a relatively uniform distribution or density of the cloth across the width of the working face adapted for efficient operation upon either hard or soft work. It will also be observed that the multiplicity of folds formed by the nested and relatively closely spaced V or N-shaped elements provide a plurality of pockets substantially increasing the capacity of the buffering wheel for retaining the buffering compound applied thereto. Fig. 12 illustrates more clearly the conformity of the N-shaped folds at an inner portion of the buffering section such as would appear after the section is partially worn down and showing the multiplicity of pockets formed by the closely spaced nested folds in which the compound may be retained.

The supporting disk 18 may and preferably will comprise a relatively thin sheet metal disk having a central opening defined by a relatively short inwardly extended flange 50 of a diameter such as to fit over the arbor on which the sections are mounted, and a cardboard or like material reinforcing ring 52 of a thickness substantially equal to the height of the flange 50 may be fitted over the flange and secured to the inner face of the disk 18 preferably by staples 54 extended through the ring 52 and with the ends of the staples clinched over and against the opposite face of the metal disk 18. The annular spacing member 20 may also comprise a ring of cardboard or like material having an inside diameter substantially equal to the inside diameter of the buffering rings 12 and having an outside diameter extended beyond the diameter defined by the weaving wires 16 and corresponding substantially to the outside diameter of the supporting disk 18.

In assembling the duplex form of buffering section illustrated in Fig. 3, wherein the two buffering rings 12 are mounted on one side of the supporting disk 18 with an annular spacer 20 disposed intermediate the buffering rings, the parts are arranged in concentric relation as shown and may be secured together by a plurality of staples, preferably two circular and substantially concentric rows of staples 56, 58 extended through the entire thickness of the buffering wheel section, the staples being preferably driven through from the cloth side of the section and with the ends of the staples clinched over the outer face of the metal disk 18. In practice, one row 56 of staples is preferably disposed within the diameter defined by the weaving wires 16, and the other row 58 is disposed beyond the diameter of the weav-

ing wires, as illustrated, thus providing a row of staples on each side of the wires 16, and both rows of staples extending through the spacer 20.

In assembling the duplex buffering section illustrated in Fig. 4 wherein the two rings 12 are mounted one on either side of the supporting disk 18, one of the buffering rings 12 is first arranged concentrically with the disk 18 and with the spacer 20 intermediate the one ring and the disk, the parts being then secured together by a circular row of staples 60 disposed within the diameter of the weaving wires 16 and driven through from the cloth side with the ends of the staples clinched over the metal disk. The second buffering ring 12 is then placed on the other side of the disk 18 and secured to the previously formed section by a circular row of staples 62 disposed beyond the weaving wires 16 and extended through the entire section as illustrated.

In both embodiments of the duplex buffering sections above described, the spacer 20 may preferably be of a thickness proportionate to the thickness of the buffering rings 12 so as to effect a relatively uniform distribution of the cloth across the working face of the duplex section. The spacer also permits air to enter between the rings to produce a cooling effect.

In practice, adjacent buffering rings 12 of a duplex buffering section having V-shaped buffering elements are preferably arranged with the nested V-shaped buffering elements 14 of one ring directed opposite to those of the adjacent ring as illustrated in Fig. 2 whereby a buffering section may be assembled on an arbor to rotate in either direction with equal efficiency. A duplex buffering section having adjacent buffering rings made up of N-shaped buffering elements are provided with pockets formed in both directions by the reversely folded portions of the N and may be arranged to rotate in either direction on the arbor.

In the manufacture of the present buffering wheel sections, each buffering ring is preferably made up of a relatively large number of closely spaced and nested radial buffering elements, in which each individual buffering element is made up of a relatively small area of cloth, so that although each individual buffering element is quite flexible in itself, the cumulative effect of a relatively large number of elements in closely spaced relation provides a relatively hard working face while at the same time maintaining sufficient flexibility so that the buffering wheel is capable of performing an efficient buffering operation upon substantially any type of work encountered in practice. The cloth from which the buffering elements are made is preferably cut on the bias for longer wear. It will also be observed that the vertically aligned V or N-shaped formation of the buffering elements permits lateral spreading of the legs or wings of the closely spaced and nested elements when they are engaged by the work to be buffered so as to cover a relatively wider buffering area with maximum uniformity of buffering surface and avoiding streaking of the work. The present buffering wheel sections are also economical in use since the relatively wider working face of each section and particularly a duplex section enables a buffering wheel of a predetermined width to be made up of relatively fewer sections. For example, six of the present duplex sections will make up a buffering wheel or roll of a width equal to that obtained by using nine of the prior sections so that a substantial saving in initial cost is afforded to the customer.

From the above description, it will be observed

that the present structure of buffering wheel may be economically manufactured, and provides a relatively wide buffering face with a substantially uniform density or distribution of the cloth across the working face to form a relatively flexible and resilient buffering wheel having a plurality of pockets for retaining a buffering compound and adapted for universal use upon various types of work to be buffered.

While the preferred embodiment of the invention has been herein illustrated and described, it will be understood that the invention may be embodied in other forms within the scope of the following claims.

Having thus described the invention, what is claimed is:

1. As a new article of manufacture, a buffering wheel section, comprising: a ring of elongated individual cloth buffering elements initially of rectangular configuration, the individual cloth buffering elements having their longitudinal axes substantially coinciding with radii of the buffering wheel section and being composed of a small number of plies so that the element is flexible and not stiff, said buffering elements also being folded longitudinally thereof to provide confronting wing portions extending circumferentially in the same general direction from the longitudinal fold between said wing portions, one of said wing portions being reversely folded on itself to provide more plies therein than are present in the other wing portion whereby one wing portion is rendered more flexible than the other, the inner end of each buffering element being compressed and bunched into a solid substantially cylindrical form and disposed in side by side relation with respect to adjacent buffering elements in said ring, said buffering elements being partially nested radially outwardly from their bunched inner ends and being otherwise disconnected from one another except at their bunched inner ends, the bunching of the inner ends of said buffering elements cooperating with the flexibility of the same to effect flaring of the unbunched portions and the separation of the plies thereof at and near the working face of the buffering wheel section when in use, whereby to facilitate air cooling thereof and to impart to the working face of the buffering wheel section a honeycomb structure of broken appearance formed by the separation of said plies and the interstices between adjacent plies of the individual buffering elements; a rigid disk; and means extending through and fastening the inner bunched ends of said buffering elements to said disk, said honeycomb structure allowing the individual buffering elements at the working face of the wheel to flex both radially and laterally about the fastened bunched inner ends of said buffering elements when the work is pressed against the wheel to impart nonstreaking characteristics to the finish on the work.

2. As a new article of manufacture, a duplex buffering wheel section, comprising: a pair of confronting rings, each ring including a plurality of elongated individual cloth buffering elements initially of rectangular configuration, the individual cloth buffering elements having their longitudinal axes substantially coinciding with radii of the buffering wheel section and being composed of a small number of plies so that the element is flexible and not stiff, said buffering elements also being folded longitudinally thereof to provide confronting wing portions extending circumferentially in the same general direction from the longitudinal fold between said wing portions, one of said wing

portions being reversely folded on itself to provide more plies therein than are present in the other wing portion whereby one wing portion is rendered more flexible than the other, the inner end of each buffering element being compressed and bunched into a solid substantially cylindrical form and disposed in side by side relation with respect to adjacent buffering elements in said ring, said buffering elements being partially nested radially outwardly from their bunched inner ends and being otherwise disconnected from one another except at their bunched inner ends, the bunching of the inner ends of said buffering elements cooperating with the flexibility of the same to effect flaring of the unbunched portions and the separation of the plies thereof at and near the working face of the buffering wheel section when in use, whereby to facilitate air cooling thereof and to impart to the working face of the buffering wheel section a honeycomb structure of broken appearance formed by the separation of said plies and the interstices between adjacent plies of the individual buffering elements; a rigid disk disposed between said pair of buff-

ing rings; and means connecting together in spaced relation said pair of buffering rings to form a unitary duplex structure, said means including mounting disk means and means extending through said mounting disk means, rigid disk and the inner bunched ends of said buffering elements and fastening said inner bunched ends of said buffering elements to said rigid disk and mounting disk means, said honeycomb structure allowing the individual buffering elements at the working face of the wheel to flex both radially and laterally about the fastened bunched inner ends of said buffering elements when the work is pressed against the wheel to impart nonstreaking characteristics to the finish on the work.
